UNITED STATES PATENT OFFICE.

ARTHUR E. HANDY, OF PROVIDENCE, RHODE ISLAND, ASSIGNOR TO THE RHODE ISLAND ELEVATOR AND MACHINE COMPANY, OF PROVIDENCE, RHODE ISLAND, A CORPORATION OF RHODE ISLAND.

CONTROLLING DEVICE.

No. 865,383.

Specification of Letters Patent.

Patented Sept. 10, 1907.

Application filed December 31, 1904. Serial No. 239,179.

To all whom it may concern:

Be it known that I, ARTHUR E. HANDY, a resident of the city of Providence, in the county of Providence and State of Rhode Island, have invented certain new and useful Improvements in Controlling Devices; and I do hereby declare that the following is a full, clear, and exact description thereof, reference being had to the accompanying drawings, and to the letters of reference marked thereon, which form a part of this specification.

This invention relates to controlling devices and has for its object to produce a device for automatically controlling the flow of electric current to the motor whereby the armature resistance may be automatically removed gradually or step by step from circuit during the starting of the motor. To accomplish this I provide in circuit with the armature of the motor, the usual starting resistance, and provide a plurality of contact fingers arranged to be successively operated to in turn remove portions of the starting resistance from the circuit, whereby the armature is permitted to start up gradually and build up in speed until normal operation results. In practice I divide the armature resistance into sections and provide a contact finger for each of the several sections, each finger being arranged to make contact successively after the main switch is closed, thereby cutting out the sections of resistance to lower the ohmic resistance of same to which the armature current is subjected, thus permitting the speed of said armature to increase gradually until the full voltage has been applied to the armature. The contact fingers being thus successively caused to make the necessary connection to successively remove the sections of the armature resistance from the circuit until the desired speed has been obtained.

By my improved construction the operation of closing the main switch and then automatically cutting out the resistance step by step is accomplished with the employment of but one coil for both operations. To accomplish this result with but one coil I construct an ordinary solenoid magnet and partially inclose its coil in an iron frame, said frame forming a field about said coil. The solenoid core or plunger is connected to operate the main switch so that when said core is up the said switch is closed, thereby completing the circuit to the motor. When the core is in its raised position said solenoid and its field frame naturally form an electro-magnet, the solenoid core or armature forming the north pole and the lower ends of the field frame forming a divided south pole. When the core is in this position the said electro-magnet acts with great increased force on its armatures 46 to draw them up.

These armatures in rising, mechanically release the series of contact fingers one at a time to cut out the rheostatic resistance step by step as described above. 55

The invention consists of other novel features and parts and combinations of the same as will be fully described hereinafter and then pointed out in the appended claims.

A practical embodiment of the invention is represented in the accompanying drawings, forming a part of this specification, in which similar characters of reference indicate corresponding parts in all the views.

In the drawings: Figure 1—is a front elevation showing the general arrangement and construction of my device. Fig. 2—is a detailed view illustrating the contact fingers in their raised position with inner ends engaging the controlling plate. Fig. 3—is the mechanism actuated by the solenoid core for raising all of the fingers simultaneously out of the contact position. 70 Fig. 4—is a plan view showing the pivoted double or two wing armature. Fig. 5—is a detailed view in perspective showing the field frame. Fig. 6—is a diagrammatic view illustrating the arrangement of the circuits also a theoretical connection is shown illustrating how the switches 1 to 10 inclusive may be controlled through the movement of the armature 46 when acted upon by energizing the coil 12.

Referring to the drawings, at 11 is the plate of slate, or other non-conducting material on which the operating mechanism is mounted. At 12 is an ordinary coil having a core 13 forming a solenoid. Extending upward from the upper end of this core is the rod 14 on which rod is supported the contact arm or main switch bar 15 carrying the usual contacts 16—16. At 17—17 are contacts which when connected together through the arm 15 complete the circuit to the motor, the contacts 18—18 are in this instance described as stops or rests to support the said solenoid and its connecting mechanism when in its down position. To the lower end of the core is attached the cross bar 19 which bar is operatively connected at either end to the levers 20—20, (see Figs. 1 and 3). These levers are pivoted at 21 to the plate 22, their outer ends being slotted at 23 to engage the pins 24—24 in the ends of 95 said bar, and admit of the desired motion.

Pivoted at 25 on the lower end of the plate 22 is a short arm 26. The connecting rod 27 which is insulated at 28 on its front edge is pivotally connected at 29 and 30 to each of the said arms 20 and 26. By 100 this arrangement both of these connecting rods 27—27 which are located at either end of the bar, are made capable of being moved both forward and back, as indicated by the dotted lines in Fig. 3, as the said arms

are moved up and down by the action of the solenoid plunger.

Located below the coil 12 are the ten contact fingers arranged in two groups of five each and pivotally supported at 32 in the brackets 31-31 on either side of the center line these fingers are not insulated from each other. They are numbered from 1 to 10 inclusively, the numbers running alternately first on one side and then the other. The outer end of each of these fingers is pressed downward by the spring 35 (see Fig. 2) which spring is mounted in the support 36 that is held in place by a bracket not shown. These ends have secured to them a flexible contact brush 35^a and when allowed to drop makes a connection with the contact 23 thereby cutting out a section of the resistance as above described. The opposite ends of the fingers 36-36 project inward toward the center from the pivoting point and are brought close together side by side as illustrated at 34-34 in Figs. 1 and 2.

20 At 37 is a controller plate supported from the bearings 38-38 by the rods 41-41 to slide vertically either up or down and control the dropping of the contact fingers. The back of this plate is insulated at 39-39 (see Fig. 2) where it engages said fingers. This plate

25 is made a little longer at 40 on its lower left hand edge so that when the said plate is raised the lower finger 1 on the right side will be released by the plate to fall and make the contact first, then 2 on the left side and so alternate back and forth one after the other.

30 At 42 is the field frame preferably made of iron incasing two sides and the top of the coil 12. This frame is supported from the switch board 11 by bolts through the ears 43-43. Fixed across the lower portion of this frame between the two ends is the brass plate 44 on which is supported the said coil 12. Ears 45-45 extend downward from each of the ends of the frame. In these ears are pivotally hung the armatures 46-46. These armatures are counter-balanced by weights 47-47 at their outer ends, the said weights being for the 40 purpose of assisting in raising the armatures when they are down and farthest away from the influence of the electro-magnet. These weights are hung at such an angle that when the armatures are down they will not be attracted by the magnetism in the field frame, but

45 be in a position to exert their greatest lifting power on the armature. These armatures 46-46 are connected to the controlling plate 37 by the connecting rods 48-48. To regulate the traveling speed of the upward stroke of the armature and plate I have connected said plate by means of the rod 49 to the piston 50. This piston slides up and down in the cylinder 51 and has a series of air inlet holes 52 in its bottom plate 53. Over these air holes is fitted a thin rubber disk which disk serves as a gravity valve to close the 55 said holes when the piston is rising. An air cock 54 is tapped into the bottom of the cylinder which may be opened to admit any desired quantity of air thereto and thereby regulate the upward speed of the piston in the cylinder.

60 The operation of the device may be further described as follows: In starting, the hand switch 60 (see Fig. 6) is moved to the terminal 61 and the current from the main 62 passes through the coil 12 energizing it and causing its core 13 to rise and close the main switch, completing the circuit between the terminals

63 and 64 and allowing the current to pass through this switch, conductor 65, resistance coil 66, and through the armature 67 and series winding 68 to the opposite main 69. The circuit is thus closed through the armature and all of the armature resistance. The path 70 for the current of the shunt field around the armature is provided through the winding 70 and conductor 71. When the core 13 has risen and closed the air gap between it and the frame, the pull on the swinging armature is greatly increased as the solenoid core then 75 acts as the north pole, and the two lower ends of the field frame serve as a divided south pole. The speed with which the armatures rise is nicely controlled by the action of the dash pot which in turn controls the falling of the contact fingers through the movement of 80 the controlling plate 37 attached thereto. After the circuit has been closed a predetermined time, the magnet armatures 46-46 have raised the controlling plate 37 sufficiently to release the contact finger 1, allowing it to fall and close the circuit, which is represented by the correspondingly numbered switch in Fig. 6, to short-circuit the first section of the resistance 85 66, thereby permitting the speed of the motor to further increase.

The speed of the piston in the dash pot is so controlled that after a second predetermined period the controlling plate 37 has ascended sufficiently to enable contact finger 2 to fall, thereby closing the circuit 2 to short-circuit a second section of the resistance and thus again increase the speed of the motor. The cutting out of this resistance step by step as the said controlling plate is raised, takes place gradually and the counter-electro motive force is thus built up in the armature gradually which building up is due to the increased speed of the said armature until the entire 100 resistance has been cut out by the falling of the eighth finger. The falling of finger 9 then completes the circuit to cut out a portion of the series winding, as illustrated in Fig. 6, and the falling of finger 10 cuts out the balance of this series field winding causing the said 105 motor to then run as a shunt wound machine. The cutting out of the series field and causing the machine to run as a shunt motor is done more particularly when the device is used in elevator work.

When it is desired to stop the motor the switch 60 is 110 opened thereby breaking the circuit and allowing the core 13 of the solenoid to fall and open the main switch. The falling of this solenoid core operates through the arms 20 and 26, as above described, to throw forward the insulated connecting rods 27-27 to engage the 115 underside of each of the two series of fingers and raise them all at once from their contact positions. The armatures 46-46 then fall being retarded by the dash pot and the plate 37 is carried down over the ends of said fingers to hold them up clear of the contacts. The 120 above described operation is performed each time the motor is started and stopped.

Some of the essential features of this device are, that it has but one coil which serves a double purpose, first it acts on its core as a solenoid to draw it up and close the main switch, and then it is automatically transformed into an electro-magnet which acts on another armature to draw up a plate and release the contact fingers mechanically one by one to cut out the resistance step by step a section at a time. By thus oper- 130

ating these fingers they make and break their connection quickly, do away with the multiple solenoid or magnet control system and also the objectional sliding contact system, I also materially simplify the mechanism for making the contacts, obtain a positive action, a quick make and break contact, and reduce the expense of manufacture to a minimum.

My invention is not restricted to the precise construction and arrangement of parts herein shown and 10 described nor to the various details thereof, as the same may be modified or re-arranged in various particulars without departing from the spirit and scope of my invention, one practical embodiment of which has been herein illustrated and described without attempting 15 to show all of the various forms and modifications in which my invention might be embodied.

Having thus described my invention, what I claim as new and desire to secure by Letters Patent, is:

1. An electric controller comprising an electro magnet 20 provided with a plunger core, an armature for said magnet, a resistance, means positively connected with and controlled by the armature to permit the cutting out of said resistance step by step, and means operated by the plunger core to return said cutting out means to its normal position 25 when said magnet is deenergized.
2. An electric controller comprising an electro magnet provided with a plunger core, an armature for said magnet, a resistance, a plurality of circuit closing fingers, means positively connected to said armature to successively release said fingers to cut out said resistance step by step, and means operated by the plunger core for simultaneously rendering all of said fingers inoperative.
3. An electric controller comprising an electro magnet provided with a plunger core, an armature for said magnet, 35 a resistance, a plurality of circuit closing fingers, means positively connected to said armature to successively release said fingers to cut out said resistance step by step, means for controlling the intervals between the successive operations of said fingers, and means operated by the 40 plunger core for simultaneously rendering all of said fingers inoperative.
4. An electric controller comprising an electro magnet provided with a plunger core, an armature for said magnet, a resistance, a plurality of circuit closing fingers, means 45 to hold said fingers normally inoperative, connections between said holding means and said armature, whereby the fingers are successively released to cut out the resistance step by step, and means operated by the plunger core to simultaneously render all of said fingers inoperative.
5. An electric controller comprising an electro magnet provided with a plunger core, an armature for said magnet, a resistance, a plurality of circuit closing fingers, a plate 50 connected to said armature and engaging the contiguous ends of all of said fingers, whereby movement of the plate permits said fingers to successively drop to cut out said resistance step by step, and means operated by the plunger core to simultaneously render all of said fingers inoperative.
6. An electrical controller comprising an electro magnet 60 provided with a plunger core, an armature for said magnet, a resistance, a plurality of circuit closing fingers arranged in sets, means connected to the armature to alternately release the fingers of each set to cut out said resistance step by step, and means operated by the plunger core for 65 simultaneously rendering all of said fingers inoperative.
7. An electric controller comprising an electro magnet provided with a plunger core, an armature for said magnet, a resistance, a plurality of circuit closing fingers arranged 70 in sets, a plate connected to said armature and engaging the contiguous ends of the fingers of each set, said plate being constructed to alternately release the fingers of each set to cut out said resistance step by step, and means operated by the plunger core to simultaneously render all of said fingers inoperative.
8. An electric controller comprising an electro magnet 75 provided with a plunger core, an armature for said magnet,

a resistance, a plurality of circuit closing fingers arranged in sets, a plate interposed between the sets of fingers and engaging all of them, the engaging portion of the plate on one side being wider than the corresponding portion on the other side, whereby the fingers of each set are alternately released to cut out said resistance step by step, and means operated by the plunger core to simultaneously render all of said fingers inoperative.

9. An electric controller comprising an electro magnet 85 provided with a plunger core, an armature for said magnet, a resistance, a plurality of circuit closing fingers, means positively connected to the armature to successively release said fingers to cut out said resistance step by step, and a pivoted member connected to the plunger core for 90 simultaneously rendering all of said fingers inoperative.

10. An electric controller comprising an electro magnet provided with a plunger core, an armature for said magnet, a resistance, a plurality of circuit closing fingers, means to hold said fingers normally inoperative, connections between said holding means and said armature, whereby the fingers are successively released to cut out the resistance step by step, and a pivoted member connected to the plunger core to simultaneously render all of said fingers inoperative.

11. An electric controller comprising an electro magnet provided with a plunger core, an armature for said magnet, a resistance, a plurality of circuit closing fingers arranged in sets, means connected to the armature to alternately release the fingers of each set to cut out said resistance step by step, and pivoted members connected to the plunger core to simultaneously render all of said fingers inoperative.

12. An electric controller comprising an electro magnet provided with a plunger core, pivotally supported armatures for said magnet provided with counterweights, a resistance, a plurality of circuit closing fingers, means positively connected with said armatures to successively release said fingers to cut out said resistance step by step, and means operated by the plunger core for simultaneously rendering all of said fingers inoperative.

13. An electric controller comprising an electro magnet provided with a plunger core, a main contact carried by said core, an armature, a resistance, a plurality of circuit closing fingers, means positively connected with said armature to successively release said fingers to cut out the resistance step by step, and means operated by the plunger core for simultaneously rendering all of said fingers inoperative.

14. An electric controller comprising an electro magnet provided with a plunger core, an armature for said magnet, a resistance, a plurality of circuit closing fingers, a plate connected to said armature and engaging the contiguous ends of said fingers, whereby movement of the plate permits said fingers to successively drop to cut out said resistance step by step, means connected to said plate to regulate the speed of movement thereof, and means operated by the plunger core to simultaneously render all of said fingers inoperative.

15. An electric controller comprising an electro magnet provided with a plunger core, pivoted armatures for said magnet provided with counterweights, a resistance, a plurality of circuit closing fingers, a plate connected to said armatures and engaging the contiguous ends of said fingers, whereby movement of the plate permits said fingers to successively drop to cut out said resistance step by step, a dash pot having its piston connected to said plate to regulate the speed thereof, and means operated by the plunger core to simultaneously render all of said fingers inoperative.

16. An electric controller comprising an electro magnet, a resistance, a main contact, a plurality of contact fingers, means for supporting said contact fingers in normally inoperative position, and means operated by said magnet to operate said main contact and subsequently to successively withdraw the support from said fingers to cut out the resistance step by step.

17. An electric controller comprising an electro magnet, a resistance, a main contact, a plurality of contact fingers, means for supporting said contact fingers in normally inoperative position, means operated by said magnet to move

- said main contact and subsequently to successively withdraw the support from said fingers to cut out said resistance step by step, and means to simultaneously disengage all of said fingers when said magnet is deenergized.
- 5 18. An electric controller comprising a motor, a resistance, a main switch, contact fingers, an electro magnet having one of its poles divided, a plunger core forming the other pole of said magnet, a plurality of pivotally hung armatures, means whereby the raising of said core 10 closes said main switch and causes an increase of the magnetic force of said magnet to operate said armatures, and means operated by said armatures for successively releasing said contact fingers to cut out said resistance step by step.
- 15 19. An electric controller comprising a motor, a resistance therefor, a main switch, contact fingers, an electro magnet having one of its poles divided, a plunger core forming the other pole of said magnet, an armature, means whereby the raising of said core closes said main switch 20 and causes an increase of the magnetic force of said magnet to operate said armature, means moved by said armature to release said contact fingers intermittently to cut out said resistance step by step, and means for controlling the speed of said armature.
- 25 20. An electric controller comprising a motor, a resist-

ance therefor, a main switch, a spring actuated contact fingers, an electro magnet provided with a plunger core, an armature for the magnet, means whereby the raising of said core closes said main switch and causes an increase in the magnetic force of said magnet to draw up said armature, means connected to the armature and moving therewith to release said contact fingers intermittently to cut out said resistance step by step, means for controlling the speed of said armature, and means connected to the core to simultaneously raise all of said fingers and break their connection when the magnet is deenergized.

30 21. An electric controller comprising an electro magnet provided with an armature, a resistance, a plurality of circuit closing fingers provided with arms or extensions, a plate to engage said arms or extensions, connections between said plate and armature, and automatic means for simultaneously moving all of said arms or extensions out of the plane of movement of said plate and in a position to be engaged thereby when said magnet is deenergized.

40 In testimony whereof, I have hereunto set my hand this 30th day of December A. D. 1904.

ARTHUR E. HANDY.

In presence of—

HOWARD E. BARLOW,
E. I. OGDEN.
